UNITED STATES PATENT OFFICE.

WILLIAM E. GREENAWALT, OF DENVER, COLORADO.

ELECTROLYTIC APPARATUS.

1,214,775.

Specification of Letters Patent.

Patented Feb. 6, 1917.

Application filed August 18, 1913. Serial No. 785,256.

To all whom it may concern:

Be it known that I, WILLIAM E. GREENAWALT, a citizen of the United States, and resident of the city and county of Denver, 5 State of Colorado, have invented certain new and useful Improvements in Electrolytic Apparatus.

It relates more particularly to the electrode bell (or electrode cell), and has for its 10 object the overcoming of certain constructional difficulties in securing the diaphragm, and in collecting and withdrawing electrode gases from the electrode bell.

One of the difficulties in the construction 15 of electrolytic apparatus, especially if corrosive solutions, such as copper sulfate, are used as the electrolyte, is, that the ordinary materials of construction cannot be used. Copper and lead are frequently used instead 20 of iron, but these metals lack strength, are difficult to shape, and are not wholly unaffected. Iron bolts are cheap, highly satisfactory and are always available in numerous standard sizes, but unless suitable protection is made for their protection, they cannot 25 be used.

It is the object of this invention to so protect the iron bolts, in the construction of the electrode bell, that they may be used without 30 serious injury. Under certain conditions, it also becomes difficult to collect the released gases, due to electrolysis, such as oxygen and ozone, if, for example, copper sulfate is used as the electrolyte. The difficulty is increased by the type of bell construction herein suggested.

Referring to the accompanying drawing, Figure 1 shows a transverse section of the apparatus and Fig. 2 a longitudinal section. 40 The right half of the drawings represents a slight modification of the left half.

In the figures, 1 represents an electrolyte tank in which is suspended the anode bell 2, and within the anode bell is suspended the 45 anode 5. The cathode is shown at 14.

Referring to the anode bell, 3 represents a diaphragm, taken as a whole, and is composed, preferably, of a frame 3^a, a frame 3^b, and a diaphragm fabric 3^c interposed between the two frames and thus held in position. In the right hand half of the figures is shown a modified arrangement, in which only the frame 3^a is used to prevent the cloth or fabric from ballooning upward by

the released gases, and slants slightly 55 toward the outside periphery of the frame.

In the anode bell, 11 is a top piece above the diaphragm and forms the side of the anode bell, 4 is a bottom piece below the diaphragm, and 12 a bolt by means of which 60 the various parts are securely bolted together, and thus forming the anode bell. In this way the anode bell can be constructed quite free from leakage. Ordinary iron bolts are preferably used in the construction. The bottom piece 4 is provided with countersunk holes or grooves for the bolt heads, and when the bolts are in position and the apparatus constructed, the bolt heads and bolts are protected by pieces of 70 wood or hard coal tar, 6, which effectively prevents the electrolyte from coming in contact with the iron. The preferred way of protecting the bolt heads is to dip a plug or strip of wood in hot coal tar and then insert the plug or strip into the groove, and over the bolt head. The coal tar will set and thus hold the plug or strip in position while at the same time exclude any possibility of the electrolyte coming in immediate contact 75 with the bolt. The nuts, not being in contact with the electrolyte, may be tightened as desired. The coal tar in the lower piece 80 also acts as an insulator for the current. In the diaphragm frame, 15 represents cross-pieces to support the fabric at the intervals desired. There is danger, in this construction of the anode bell, from gases becoming 85 trapped in the under side of the diaphragm, and thus reduce the efficiency of the process. 90 To overcome this, means, such as auger holes or saw cuts, 13, are provided for the escape of such gases. In the construction, as shown on the left half of the drawings, the escape of the gases is facilitated by the 95 sloping diaphragm which conducts the gases toward the escape holes, so that they are at once removed from the sphere of influence of the electric current. The removal of the anode gases is ordinarily taken care of by 100 providing for a tight anode bell, but this presents certain undesirable features. It is quite impossible to make the anode bell tight, and if the suction is inward the gases will be diluted; if the pressure is outward 105 the escape of gases cannot be prevented. To overcome these difficulties the anode is arranged with a liquid seal 8, into which is

fitted a hood 7, and the gases collected in the hood are withdrawn through the duct 9. The anode is perforated so as to allow the gases to enter the hood as rapidly as formed, and so as not to interfere with the electrolytic action. To prevent any gases from escaping from the outside of the anode, a flange 16 is projected downwardly along the outside edge. This flange should be insulated by some insulating paint or coating.

The bell may be suspended by the rods 17, and the anode by the rods 10, from the outside rim of the liquid seal. These rods may also act as the electrical conductors to the anode. The current enters the rod 10, passes to the anode 5, through the electrolyte, and to the cathode 14. It may be withdrawn from the cathode in any convenient way.

It is evident that the anode bell may also be used as a cathode bell by reversing the direction of the current, or, in general, it may be designated as an electrode bell, and may contain either the anolyte and anode, or catholyte and cathode. Nor is it intended to limit the invention to this particular form of electrode bell; various modifications are obvious, and it is thought that the full description given will enable any one skilled in the art to make such modifications without difficulty.

If desired the electrode bell may be oscillated from the suspending rods 17; the anodes may remain stationary, and the raised bottom cathode piece serve as a guide.

The bolt heads are best protected by inserting into the countersunk holes an acid proof cement, which, on setting, completely fills the hole and thus effectively protects the bolt head from the action of the electrolyte; or the bolt head may be incased in lead. If the bolt head is incased in lead it may be desirable, in some instances, to omit the bottom protective pieces 6, and clamp the diaphragm fabric directly between the diaphragm frames.

I claim:

1. In electrode bell of electrolytic apparatus, a top piece forming the sides of the electrode bell; a bottom piece; a diaphragm bolted between the top and bottom pieces; means of protecting the bolt head from the direct action of the electrolyte, and means, in the frame so constructed, for the escape of gases from the under side of the diaphragm.

2. In electrode bell of electrolytic apparatus, a top piece forming the sides of the electrode bell; a bottom piece; a diaphragm supported by a diaphragm frame and bolted between the top and bottom pieces; means with the bottom piece of protecting the bolts from the corrosive action of the electrolyte,

and means in said frame work for the escape of gases from the under side of the diaphragm.

3. In electrode bell of electrolytic apparatus, a top piece forming the sides of the electrode bell; a bottom piece; a diaphragm bolted between the top and bottom pieces; means with the bottom piece of protecting the bolts from the action of the electrolyte, and means in the bottom piece for the escape of gases from the under side of the diaphragm.

4. In electrode bell of electrolytic apparatus, a top piece forming the sides of the electrode bell; a bottom piece; a diaphragm bolted between the top and bottom pieces; means with the bottom piece of protecting the bolts from the corrosive action of the electrolyte; means for the escape of gases from the under side of the diaphragm; a perforated electrode in the electrode bell; a hood over the electrode, and a liquid seal between the electrode and the hood.

5. In electrode bell of electrolytic apparatus, an electrode in said electrode bell; a hood over the electrode; a liquid seal between the hood and electrode for the collection and withdrawal of electrode gases, perforations in the electrode through which the electrode gases are delivered from the under side of the electrode into the hood, and a flange projecting downwardly along the outside edge of the electrode.

6. In electrode bell of electrolytic apparatus an electrode in said bell; a hood for the collection of electrode gases; a liquid seal between the electrode and hood; perforations in the electrode through which the gases are delivered to the hood, and means connected with the outside rim of the seal for the suspension of the electrode and the introduction of the electric current.

7. In electrolytic apparatus, an anode; a hood; a liquid seal between the anode and hood, perforations in the anode through which the electrode gases are delivered to the hood, and cross-pieces interposed between the electrodes suspended by supports passing between the edge of one of the electrodes and sides of the electrolyte tank, and means for oscillating the cross-pieces.

8. In electrolytic apparatus, an electrode; a hood; a liquid seal between the electrode and the hood, and means of oscillating the electrode, relatively to the electrolyte.

9. In electrolytic apparatus, an anode; a hood; a liquid seal between the anode and the hood, and means of moving the anode and hood relatively to the cathode.

10. In electrode bell of electrolytic apparatus an electrode in said bell, a hood for the collection of the electrode gases, a liquid seal between the electrode and the hood, perforations in the electrode through which the gases are delivered to the hood, and means

connected with the outside rim of the seal for suspending the electrode in the electrolyte.

11. In electrolytic apparatus an anode, a hood, a liquid seal between the anode and hood, perforations in the anode through which the anode gases are delivered to the hood, cross-pieces interposed between the

anode and cathode suspended by supports passing between the edge of the anode and 10 sides of the electrolyte tank, and means for moving the cross-pieces.

WILLIAM E. GREENAWALT.
